CLAIM
The ornamental design for a housing for a digital deadbolt
lock, as shown and described.

(21) **Appl. No.:** **29/559,069**

DESCRIPTION

(22) **Filed:** **Mar. 24, 2016**

FIG. 1 is a front elevation view of a housing for a digital
deadbolt lock, in accordance with my new design;
FIG. 2 is a side elevation view of the housing for a digital
deadbolt lock shown in FIG. 1, taken from the left side of
FIG. 1;

(51) **LOC (10) Cl.** **08-07**

FIG. 3 is a side elevational view of the housing for a digital
deadbolt lock shown in FIG. 1, taken from the right side of
FIG. 1;

(52) **U.S. Cl.**

FIG. 4 is a rear elevational view of the housing for a digital
deadbolt lock shown in FIG. 1;

(53) **USPC** **D8/331; D8/330**

FIG. 5 is a top plan view of the housing for a digital deadbolt
lock shown in FIG. 1;

(58) **Field of Classification Search**

FIG. 6 is a bottom plan view of the housing for a digital
deadbolt lock of FIG. 1; and,

USPC D8/330, 331, 334, 300, 301, 350; 70/14,

FIG. 7 is a perspective view of the housing for a digital
deadbolt lock shown in FIG. 1, taken from the front, top, and
left side of FIG. 1.

70/20-22, 57, 57.1, 284-286, 314,

The broken lines illustrate environmental structure which

70/DIG. 44, 266, 277, 271

forms no part of the claimed design.

CPC E05B 9/00; E05B 9/02; E05B 2009/006;

E05B 49/00
